UNITED STATES PATENT OFFICE.

CHARLES W. MANZEL, OF BUFFALO, NEW YORK.

DESIGN FOR A LEAF-SPRING-LUBRICATING TOOL.

51,729.

Specification for Design.

Patented Feb. 5, 1918.

Application filed May 3, 1915. Serial No. 25,622. Term of patent 14 years.

To all whom it may concern:

Be it known that I, CHARLES W. MANZEL, a citizen of the United States, residing at Buffalo, in the county of Erie and State of New York, have invented a new, original, and ornamental Design for Leaf-Spring-Lubricating Tools, of which the following is a specification, reference being had to

the accompanying drawing, forming part thereof, and which is a perspective view of the lubricator embodying my design.

I claim:—

The ornamental design for a leaf spring lubricating tool, as shown.

CHARLES W. MANZEL.
